UNITED STATES PATENT OFFICE.

ELDA G. SMITH, OF SYRACUSE, NEW YORK, ASSIGNOR TO CROUSE-HINDS COMPANY, OF SYRACUSE, NEW YORK, A CORPORATION OF NEW YORK.

CONDUIT OUTLET-BOX.

1,314,372.

Specification of Letters Patent. Patented Aug. 26, 1919.

Application filed July 13, 1917. Serial No. 180,303.

To all whom it may concern:

Be it known that I, ELDA G. SMITH, a citizen of the United States, and a resident of Syracuse, in the county of Onondaga and State of New York, have invented a certain new and useful Conduit Outlet-Box, of which the following is a specification.

This invention relates to conduit outlet boxes and has for its object a particularly simple and efficient conduit outlet box especially applicable for inclosing the service wires for the controllers of electric railway cars, and the invention consists in the novel features and in the combinations and constructions hereinafter set forth and claimed.

In describing this invention, reference is had to the accompanying drawings in which like characters designate corresponding parts in all the views.

Figure 1 is a side elevation of this conduit outlet box showing the same applied to a railway car; the contiguous part of the body of the car being shown in section, and also the contiguous part of the conduit inclosing the service wires being also shown.

Fig. 2 is a plan view of the conduit outlet box.

Fig. 3 is a sectional view on line 3-3, Fig. 2.

This conduit outlet box comprises a body having an opening in one side thereof, a tubular projection extending from the side opposite the open side and means on a lateral side of the body for connection to electric conduits, and a detachable closure for the opening.

1 designates the body of the box, the body having an opening 2 in one side as its lower 40 side, the opening extending over practically the entire area of said side, in order to give greatest accessibility to the wires passing through the box.

3 is a tubular projection rising from the 45 wall 4 opposite the open side 2, the wall 4 having a substantially flat upper face for lying against the under face of the flooring 5 of an electric railway car 6. The tubular projection 3 is oblong in general 50 form with rounding sides at the ends of the oblong, and projects through an open-

ing 7 in the bottom of the floor 5 of the car so that its upper end opens into the controller box 8. The body 1 of the box is also provided on one of its lateral sides with 55 means for connection to the conduits inclosing the service wires and as here shown, it is provided with a horizontal nipple or boss 9 having a pair of threaded passages 10 for connection with the conduits 11 enclosing 60 the feed wires, the passages opening into the body of the box 1.

12 is a closure for the open side 2, this closure being detachably secured in position in any suitable manner as by screws 65 13 extending through marginal flanges on the closure 12 and threading into openings in a box 1 or in flanges projecting from the box. The box 1 is provided with means as lugs or flanges 14 projecting laterally 70 from the top thereof near the upper flat face of the wall 4 and underlying the floor of the car body, and through which fastening means as screws are passed.

The body is preferably cylindrical in general 75 form with flat upper and lower ends and the tubular projection 3 extends upwardly at one side of the center of the box, and the boss 10 projects outwardly from the cylindrical wall of the body.

In use, the body is placed flatwise against the under side of the floor 5 of the car body with the tubular projection 3 extending upwardly through the car body and into the controller box, and the body is secured 85 to the floor by fastening means as screws extending through the lugs of flanges 14 and into the floor. The service wires are led into and out of the box through the conduits 11.

This conduit outlet box provides particularly simple and efficient housing for the service wires where they enter the controller box of railway cars and at the same time gives ready accessibility thereto where 95 the wires enter the controller box.

What I claim is:

An electrical conduit box comprising a body having a flat upper bearing face, means on one of the lateral sides thereof 100 for connection with a plurality of conduits, an upwardly extending tubular projection

extending from the flat upper face at a point farthest remote from said conduit connection means and having its passage greater than the combined cross sectional area of the passages of said conduit connection means, the body having its lower side open, and a closure for the open side,

substantially as and for the purpose described.

In testimony whereof, I have hereunto signed my name, at Syracuse, in the county of Onondaga, and State of New York, this 5th day of July, 1917.

ELDA G. SMITH.
